CALVERT B. COTTRELL, 3D, OF WESTERLY, RHODE ISLAND, ASSIGNOR TO C. B. COTTRELL & SONS COMPANY, OF WESTERLY, RHODE ISLAND, A CORPORATION OF DELAWARE

BED AND CYLINDER PRINTING PRESS

Application filed May 7, 1931. Serial No. 535,685.

The object of my invention is to provide certain improvements in a bed and cylinder printing press whereby the product of the press may be materially increased with a minimum movement of the impression cylinder and form bed.

My invention comprises an impression cylinder which oscillates about one and one-half revolutions on each of its forward and reverse strokes, said cylinder being operable to print one sheet and deliver a previously printed sheet tail end first on each stroke of the cylinder; two sheet feeders and two delivery mechanisms being provided, the sheet feeders being arranged to alternately feed the sheets to the under side of the impression cylinder and the two delivery mechanisms being arranged to alternately take the printed sheets tail ends first from the upper side of the impression cylinder.

My invention further comprises a bed and cylinder printing press in which the reciprocating bed carries a single form which coacts with the impression cylinder on both its forward and reverse strokes to print a single product and transfer it to two deliveries.

My invention still further comprises two inking mechanisms operable respectively to ink the form on the forward and reverse strokes of the bed; means being provided on the bed for controlling the raising and lowering of the inking mechanisms out of and into position to contact with the form on the reciprocating bed.

A practical embodiment of my invention is represented in the accompanying drawings in which:

Fig. 1 represents a side elevation of my improved bed and cylinder printing press, the parts being shown in the positions they assume when the bed and cylinder have proceeded on their forward strokes to a point where a sheet is fed to the cylinder from one feeder and a previously printed sheet which was fed from the other feeder is being transferred, tail end first to its delivery mechanism; the position of the form bed being shown in dotted lines at the end of its forward stroke.

Fig. 2 represents a detail side view of the

bed and cylinder in the positions shown in Fig. 1, and illustrating the means for controlling the operation of the left hand sheet stop and one set of grippers.

Fig. 3 represents a similar view with the bed and cylinder at the ends of their forward strokes and illustrating the means for operating the right hand stripper to transfer the tail end of the printed sheet from the cylinder.

Fig. 4 represents a similar view showing the bed and cylinder partway of their reverse strokes and illustrating the means for operating the other set of grippers and the right hand sheet stop.

Fig. 5 represents a similar view showing the bed and cylinder at the limit of their reverse strokes and illustrating the means for operating the left hand stripper for stripping the tail end of a printed sheet from the cylinder and transferring it to its delivery mechanism as the cylinder starts on its forward stroke.

Fig. 6 represents a detail top plan view of the bed and cylinder with the parts in the positions shown in Fig. 5.

Fig. 7 represents a detail view showing the tumbler cam actuated mechanism with the tumbler cam actuating pin in its normal retracted position.

Fig. 8 represents a detail view of the yielding cam for operating the tumbler cam pin on the reverse stroke of the bed.

Fig. 9 represents a similar view of the yielding cam for operating the tumbler cam pin on the forward stroke of the bed.

Fig. 10 represents a detail diagrammatic view showing the relative positions of the several parts as the first sheet to be printed on the forward strokes of the bed and cylinder has been taken by its grippers.

Fig. 11 represents a similar view as the bed and cylinder finish the printing of the first sheet on their forward strokes.

Fig. 12 represents a similar view as the bed and cylinder reach the end of their forward stroke and are about to start on their reverse stroke to deliver the first sheet tail end first to the right hand delivery mechanism.

Fig. 13 represents a similar view as the bed and cylinder reach a position on their reverse stroke where the second sheet is about to be taken by its grippers and the head end of the first sheet is released by its grippers.

Fig. 14 represents a similar view as the printing of the second sheet is started.

Fig. 15 represents a similar view as the printing of the second sheet is finished.

10 Fig. 16 represents a similar view as the bed and cylinder complete their reverse strokes and the second sheet is about to be transferred, tail end first to the left hand delivery mechanism.

15 Fig. 17 represents a view similar to Fig. 10 showing the third sheet about to be taken as the second sheet is being delivered on the forward strokes of the bed and cylinder.

20 Fig. 18 represents a similar view as the printing of the third sheet is finished.

The main frame of the printing press is denoted by 1. The form bed which is fitted to reciprocate in the main frame is denoted by 2 and its single form thereon by 3. This bed may be reciprocated by any suitable means, such for instance as a motive fluid drive, a portion only of which is represented in the accompanying drawings.

Two inking mechanisms are provided, one 30 for inking the form on the forward stroke of the bed and the other for inking the form on the reverse stroke of the bed. Each inking mechanism comprises an ink fountain 4, distributing rollers 5, form rollers 6 and an 35 electric motor 7, which motor is independent of the bed reciprocating means and drives both the distributing rollers and the form rollers continuously in one direction to ensure an even application of the ink to the 40 form 3. A cam 8 on the form bed is arranged in position to raise the form rollers of one inking mechanism out of position to contact with the form on one stroke of the bed and a cam 9 on the form bed is arranged 45 in position to raise the form rollers of the other inking mechanism out of position to contact with the form on the opposite stroke of the bed. The oscillating impression cylinder 10 is fixedly mounted in the main 50 frame 1 and it is geared at all times to the reciprocating bed through the usual gear and rack connection 11, 12. The movement of the bed is sufficient to rotate the cylinder more than one revolution, preferably about one 55 and one-half revolutions in each direction.

This oscillating impression cylinder is provided with two sets of tumbler actuated grippers 13 and 14, their tumbler cams being denoted by 15 and 16 respectively. A 60 single tumbler cam actuating pin 17 is slideable into the path of the tumbler cams 15 and 16 at the proper times to open and close the grippers 13 and 14 and is held yielding- 65 ly out of the path of the cams by the spring 18. The pin operating rock lever is pivoted

at 19 to the main frame 1 and it has one arm 20 which engages the pin to move it laterally into the path of the tumbler cams and the stud or roller on the other arm 21 of which lever is arranged in position to be engaged by the yielding cam 22 as the bed moves in one direction and by the cam 23 when the bed moves in the opposite direction.

The two oppositely disposed sheet feed tables which may be parts of any well known or approved sheet feeding mechanisms are denoted by 24 and 25 and they are arranged in position to feed the sheets to their respective grippers 13 and 14 when the grippers are at the under side of the impression cylinder.

The two sheet feed stops 26 and 27 for the tables 24 and 25 are controlled by cams 28 and 29 respectively, on the reciprocating form bed 2.

The two oppositely disposed sheet delivery mechanisms may also be of any well known or approved form, those shown herein comprising the oppositely disposed sheet strippers 30 and 31, the endless sheet carriers 32 and 33 and the two pairs of coating sheet delivery rolls 34, 35 and 36, 37. The operation of the stripper 30 is controlled by a cam 38 on the bed 2 and the operation of the stripper 31 is controlled by a cam 39 also on the reciprocating form bed.

The operation of the printing press is as follows: Presupposing the printing operation to be about to start and the parts in the positions shown in Fig. 10 of the drawings with the bed and cylinder moving on their forward strokes from the points shown in Fig. 16, the grippers 13 will close on their first sheet to be printed, fed from the table 24. During this forward printing stroke the first sheet will be fully printed as the cylinder reaches the position shown in Fig. 11. The cylinder then completes the substantially one and one-half revolutions of its forward stroke to the point shown in Fig. 12 where the tail end of the printed sheet will be brought beyond the stripper 31. The impression cylinder and bed will then start on their reverse strokes, causing the tail end of the first printed sheet to be stripped from the cylinder and transferred to the coating delivery rolls 36, 37 and endless delivery carrier 33. When the bed and cylinder reach the position shown in Fig. 13, the grippers 13 are opened to release the first printed sheet and the grippers 14 are closed onto the head end of their sheet fed from the feed table 25. When the parts reach the position shown in Fig. 14 the printing of the second sheet is started. When the parts reach the positions shown in Fig. 15 the printing of the second sheet has been completed. When the parts reach the position shown in Fig. 16 the bed and cylinder have reached the limit of their reverse move-

ments and the tail end of the second printed sheet has been brought beyond the stripper 30.

The bed and cylinder then start again on their forward stroke causing the stripper 30 to strip the tail end of the second printed sheet from the cylinder and transfer it to the coating delivery rolls 34, 35 and endless carrier 32. When the parts reach the position shown in Fig. 17 the third sheet is taken by the grippers 13 and the head end of the second printed sheet is released. Fig. 18 shows the positions of the parts as the printing of the third sheet has been completed, the parts being in the positions shown in Fig. 11. From this time on a sheet will be printed and a previously printed sheet will be delivered on each forward and reverse stroke of the bed and cylinder.

From the above description it will be seen that by feeding the sheets alternately to the under side of the impression cylinder and by transferring the printed sheets alternately from the upper side of the said cylinder the movements of the bed and cylinder are kept down to a minimum.

It will also be seen that a very rapid printing of a product can thus be accomplished in a bed and cylinder press and a larger product obtained in a predetermined time than heretofore.

It will also be seen that by providing means for driving the form rollers of both of the inking mechanisms at all times in one direction a more even distribution and application of the ink to the form may be obtained than was possible where the form rollers were rotated first in one direction and then in the opposite direction during the reciprocation of the bed.

It is evident that various changes may be resorted to in the construction, form and arrangement of the several parts without departing from the spirit and scope of my invention, and hence I do not intend to be limited to the particular embodiment herein shown and described.

What I claim is:

1. In a bed and cylinder printing press, a reciprocating form bed, and an oscillating impression cylinder operable, on each stroke, to print one sheet and deliver a previously printed sheet tail end first.

2. In a bed and cylinder printing press, a reciprocating form bed, an oscillating impression cylinder operable, on each stroke, to print one sheet and deliver a previously printed sheet, tail end first, and two inking mechanisms, one operable to ink the form on one stroke and the other on the opposite stroke of the bed.

3. In a bed and cylinder printing press, a reciprocating form bed, an oscillating impression cylinder operable, on each stroke, to print one sheet and deliver a previously

printed sheet tail end first, and two feeders operable to feed the sheets alternately to the under side of the impression cylinder from the opposite sides thereof.

4. In a bed and cylinder printing press, a reciprocating form bed, an oscillating impression cylinder operable, on each stroke, to print one sheet and deliver a previously printed sheet tail end first, two feeders operable to feed the sheets alternately to the under side of the impression cylinder from opposite sides thereof, and two deliveries operable to take the printed sheets alternately from the upper side of the cylinder in opposite directions.

5. In a bed and cylinder printing press, a reciprocating form bed, an oscillating impression cylinder operable, on each stroke, to print one sheet and deliver a previously printed sheet tail end first, two feeders operable to feed the sheets alternately to the under side of the impression cylinder from opposite sides thereof, and two deliveries operable to take the printed sheets alternately from the upper side of the cylinder in opposite directions, each delivery including a stripper operated by the bed for stripping the tail end of the printed sheet from the cylinder.

6. In a bed and cylinder printing press, a reciprocating form bed, an oscillating impression cylinder operable, on each stroke, to print one sheet and deliver a previously printed sheet tail end first, two inking mechanisms, one operable to ink the form on one stroke and the other on the opposite stroke of the bed, and two feeders operable to feed the sheets alternately to the under side of the impression cylinder from the opposite sides thereof.

7. In a bed and cylinder printing press, a reciprocating form bed, an oscillating impression cylinder operable, on each stroke, to print one sheet and deliver a previously printed sheet tail end first, two inking mechanisms, one operable to ink the form on one stroke and the other on the opposite stroke of the bed, two feeders operable to feed the sheets alternately to the under side of the impression cylinder from the opposite sides thereof, and two deliveries operable to take the printed sheets alternately from the upper side of the cylinder in opposite directions.

8. In a bed and cylinder printing press, a reciprocating form bed, an oscillating impression cylinder operable, on each stroke, to print one sheet and deliver a previously printed sheet tail end first, two inking mechanisms, one operable to ink the form on one stroke and the other on the opposite stroke of the bed, two feeders operable to feed the sheets alternately to the under side of the impression cylinder from opposite sides thereof, and two deliveries operable to take the printed sheets alternately from the upper side of the cylinder in opposite directions.

side of the cylinder in opposite directions, each delivery including a stripper operated by the bed for stripping the tail end of the printed sheet from the cylinder.

5 9. In a bed and cylinder printing press, a reciprocating form bed, and an impression cylinder arranged to oscillate about one and one-half revolutions in each direction, said cylinder being operable, on each stroke, to print one sheet and deliver a previously printed sheet tail end first.

10 10. In a bed and cylinder printing press, a reciprocating form bed, an impression cylinder arranged to oscillate about one and one-half revolutions in each direction, said cylinder being operable, on each stroke, to print one sheet and deliver a previously printed sheet tail end first, and two inking mechanisms, one operable to ink the form on one stroke and the other on the opposite stroke of the bed.

11 11. In a bed and cylinder printing press, a reciprocating form bed, an impression cylinder arranged to oscillate about one and one-half revolutions in each direction, said cylinder being operable, on each stroke, to print one sheet and deliver a previously printed sheet tail end first, and two feeders operable to feed the sheets alternately to the under side of the impression cylinder from opposite directions.

12 12. In a bed and cylinder printing press, a reciprocating form bed, an impression cylinder arranged to oscillate about one and one-half revolutions in each direction, said cylinder being operable, on each stroke, to print one sheet and deliver a previously printed sheet tail end first, two feeders operable to feed the sheets alternately to the under side of the impression cylinder from opposite sides thereof, and two deliveries operable to take the printed sheets alternately from the upper side of the cylinder in opposite directions.

13 13. In a bed and cylinder printing press, a reciprocating form bed, an impression cylinder arranged to oscillate about one and one-half revolutions in each direction, said cylinder being operable, on each stroke, to print one sheet and deliver a previously printed sheet tail end first, two inking mechanisms, one operable to ink the form on one stroke and the other on the opposite stroke of the bed, and two feeders operable to feed the sheets alternately to the under side of the impression cylinder from opposite sides thereof.

14 14. In a bed and cylinder printing press, a reciprocating form bed, an impression cylinder arranged to oscillate about one and one-half revolutions in each direction, said cylinder being operable, on each stroke, to print one sheet and deliver a previously printed sheet, tail end first, two inking mechanisms, one operable to ink the form on one stroke and the other on the opposite stroke of the bed,

two feeders operated to feed the sheets alternately to the under side of the impression cylinder from opposite sides thereof, and two deliveries operable to take the printed sheets alternately from the upper side of the cylinder in opposite directions.

15 15. In a bed and cylinder printing press, a reciprocating form bed, an impression cylinder arranged to oscillate about one and one-half revolutions in each direction, two sets of oppositely directed grippers on the cylinder, means for feeding sheets alternately to the two sets of grippers at the under side of the cylinder from opposite sides thereof, means for taking the printed sheets alternately from the cylinder, tail end first at the upper side of the cylinder in opposite directions, and means controlled by the bed for opening and closing the grippers.

In testimony, that I claim the foregoing as my invention, I have signed my name this 1st day of May, 1931.

CALVERT B. COTTRELL, 3d.
